US0D1088011S

(12) **United States Design Patent** (10) Patent No.: **US D1,088,011 S**
(45) Date of Patent: ** Aug. 12, 2025

(54) **DISPLAY SCREEN WITH GRAPHICAL USER INTERFACE**

(71) Applicant: **Airbnb, Inc.**, San Francisco, CA (US)

(72) Inventors: **Daniel Spitzer-Cohn**, San Francisco, CA (US); **Chadwick Harber**, San Francisco, CA (US); **Mark Dennis Laughlin, Jr.**, Santa Cruz, CA (US); **Tristan Wood**, San Francisco, CA (US); **Aurelio Guzman**, San Jose, CA (US)

(73) Assignee: **Airbnb, Inc.**, San Francisco, CA (US)

(**) Term: **15 Years**

(21) Appl. No.: **29/940,100**

(22) Filed: **Apr. 30, 2024**

(51) LOC (15) Cl. **14-04**

(52) U.S. Cl.

USPC **D14/485**

(58) **Field of Classification Search**

USPC D14/485-495

See application file for complete search history.

(57) **CLAIM**

The ornamental design for a display screen with graphical user interface as shown and described.

DESCRIPTION

The FIGURE is a front view of a display screen with graphical user interface showing our new design.

The peripheral dash-dot-dash lines illustrate a display screen or portion thereof and form no part of the claimed design. The dashed broken lines within the peripheral dash-dot dash lines illustrate portions of the graphical user interface which form no part of the claimed design.
